TRAY RACK

Robert C. Burnley, Louisville, Ky.

Application June 27, 1934, Serial No. 732,721
Renewed November 5, 1935

9 Claims. (Cl. 211—174)

This invention relates to tray racks and has for its object the production of a simple and efficient tray rack for the purpose of conveniently supporting a plurality of piles of trays, one above the other, in such a manner as to permit the trays to be conveniently and easily removed from the rack.

Another object of this invention is the provision of a simple and efficient means for supporting the trays at a desired elevation whereby convenient removal by the patrons of the cafeteria or restaurant while passing the tray rack will be facilitated.

A further object of this invention is the provision of a simple and efficient means for facilitating the supporting of the trays in an adjustable position whereby the rack may be raised or lowered as the trays are used or removed from the rack.

A still further object of the invention is the provision of a simple and efficient latching means for holding the tray rack in an adjusted position.

A still further object of this invention is the production of a tray rack which is light in construction and the parts of which are so arranged as to permit a waiter to carry or transport the rack without difficulty to convenient locations for service.

Other objects and advantages of the present invention will appear throughout the following specification and claims.

In the drawings:—

Figure 1 is a top plan view of the improved tray rack;

Figure 2 is a front elevation of the improved tray rack, a certain portion thereof being shown in section;

Figure 3 is a section taken on line 3—3 of Figure 1;

Figure 4 is an end elevation of the tray rack, a portion of the base being broken away;

Figure 5 is a vertical sectional view taken on line 5—5 of Figure 4;

Figure 6 is a vertical sectional view through a portion of one end of the tray rack somewhat similar to that shown in Figure 5, certain parts being removed and the sections of the rack being shown in a lowered position;

Figure 7 is a section taken on line 7—7 of Figure 2;

Figure 8 is a section taken on line 8—8 of Figure 5;

Figure 9 is a section taken on line 9—9 of Figure 7;

Figure 10 is a section taken on line 10—10 of Figure 1;

Figure 11 is a section taken on line 11—11 of Figure 10;

Figure 12 is a vertical section taken on line 12—12 of Figure 4 certain parts being eliminated.

By referring to the drawings, it will be seen that the present tray rack comprises a pair of end frames 10, and each end frame 10 comprises a base 11 having feet 12 which are adapted to rest upon the floor or other support. Each frame 10 also comprises a pair of spaced vertically extending rails 13 which are secured in any suitable or desired manner to the base 11, such as is shown in Figure 4, these rails 13 being preferably formed of metal and carrying transversely extending stop pins 14 at their upper ends. Abutment brackets 15 are carried near the lower ends of the rails 13, as shown in Figure 4.

A sectional vertically extending end member 16 is slidably mounted upon the track rails 13 of each end frame 10, through the medium of the apertured shoe blocks 17 through which apertured shoe blocks 17 extend the rails 13, as shown in Figure 7. The shoe blocks 17 extend transversely of each end member 16. These shoe blocks 17 are preferably three in number, as illustrated in the drawings. The sectional vertically extending end member 16 upon each side of the frame comprises a pair of sections 18 and 19 which are arranged in end abutting relation, the upper section 19 carrying a sleeve 20 which fits over the upper end of the lower section 18, as shown in Figure 12. The lower section 18 is notched as at 21, for receiving the transversely extending pin 22 carried by the sleeve 20 and assisting in anchoring the sleeve in position.

The lower sections 18 of the end members 16 which are mounted upon the opposite sides of the tray rack supports a transversely extending tray rack supporting rail 23, the rail being fixedly secured in any suitable or desired manner at its respective ends as illustrated in the drawings.

Due to the fact that the upper sections of the end members 16 are removable, it will be seen that only one tray supporting rail may be used if desired, or two tray supporting racks may be used, one above the other, for supporting two separate piles or groups of trays.

The upper sections 19 of the end members 16 support the transversely extending upper tray supporting rail 24, the rail being secured and anchored at its end in any suitable or desired manner. In order to hold these two sections 18

- and 19 of the end members 16 against vertical displacement, a tie rod 25 is employed near each end, the tie rod being threaded into engagement with an anchoring bracket 26, at its lower end 5 and passing through the longitudinally extending slots 27 in the upper rail 24, a nut 28 being threaded upon the tie rod 25 in each instance for preventing spreading movement of the rails 23 and 24 relative to each other. Each tie rod may 10 be provided with a laterally bent end 29 which may constitute a handle, if desired, for the purpose of facilitating the lifting or vertical adjustment of the track rack or end members 16 relative to the rails 13.
- 15 Suspended below the transversely extending tray supporting rail 23 is a substantially U-shaped hanger yoke 30, the yoke being secured at its upper ends to the rail 23 by means of suitable securing pins or bolts 31. Pivotally secured to 20 the yoke 30 are a pair of spaced trigger members 32 which may be of any suitable or desired design. Pivotally secured to these triggers 32 are arranged and supported laterally extending pull rods 33 and 34, the pull rod 33 being suspended upon a 25 link 35 which in turn is pivotally supported upon a hanger strap 36 suspended from the lower rail 23, as shown in Figure 2. This link 35 in turn supports an arm 37 which extends through the yoke 30 and supports at its opposite end an arm 38 which is in turn supported at its lower end or 30 secured to the pull rod 34. This will insure the uniform action of the pull rods 33 and 34 when the triggers 32 are actuated.
- Each pull rod 33 and 34 carries at its outer end 35 a transversely extending plate 39 which plate 39 in turn carries a pair of spaced locking fingers 40, the locking fingers 40 extending into suitable 40 sockets 41 formed in the inturned shoe blocks 17 carried upon either side of the frame, as illustrated in the drawings. The extremities of the fingers 40 are adapted to selectively engage the notches 42 formed in the rails 13 for the purpose of holding the tray supporting rails 23 and 24 and end members 16 in a vertically adjusted position 45 upon the rails 13. Suitable springs 43a are secured to the plates 39 in each instance and also to the intermediate shoes 17 upon the opposite sides of the frame so as to normally pull or hold the fingers 40 within the sockets 41.
- 50 When it is desired to vertically adjust the tray rack including the tray supporting rails 23 and 24, and end members 16 upon the vertical rails 13, the triggers 32 are compressed toward each other at their lower ends for drawing the locking fingers 40 out of engagement with the notches 42 of the rails 13. The entire tray supporting frame may then be raised to the desired vertical adjustment, any suitable or desired number of notches 42 being arranged in the rails 13 to provide for a 55 suitable adjustment.
- A coil spring 43 is anchored at its lower end, as at 44, upon the base 11, and upon each frame 10, and the upper end of this coil spring 43 is connected to a pull rod 45, a similar pull rod 45 60 being carried upon each side frame 10, the pull rod 45 in each instance being slidably mounted through the shoe blocks 17. The lower block 17 is cut out sufficiently to permit the coil spring 43 to pass therethrough when the spring is in its extended position. The pull rod 45 in each instance is provided with a notch 46 near its lower end and this notch is adapted to be engaged by 65 means of a locking finger 47 which is slidably mounted through the intermediate shoe block 17.

This locking finger 47 by engaging the notch 46 will hold the pull rod 45 in anchored engagement with respect to the adjacent end member 16 of the tray rack. A yoke 48 is carried by the locking finger 47 and extends through the intermediate shoe block 17, as shown in Figure 7 and carries coil springs 49 to normally hold the locking finger 47 in locking engagement with the pull rod 45 upon each side of the tray rack. Normally slack chains 50 are connected to the locking 10 fingers 47 upon opposite sides of the tray rack and these chains are anchored, as at 51, and 52, to the pull rods 33 and 34, the chains 50 being sufficiently slack to permit the disengaging of the locking fingers 40 from the rails 13 and at the 15 same time permit the locking finger 47 to retain its engagement with the socket 46 in the pull rod 45. In this manner, the locking fingers 40 may be disengaged from the rails 13 and the springs 43a carried by each frame 10 will be free to pull 20 the end members 16 downwardly.

The locking finger 47 upon each side of the tray rack will be held against accidental release through the medium of the trigger arm 53 carried by the transversely extending bar 54, the transversely extending bar 54 being pivotally mounted for swinging movement within the brackets 55 supported upon the end members 16 at opposite sides of the tray rack. Angularly bent handles 56 are carried by the ends of the transversely 30 extending bar 52.

When it is desired to release the locking fingers 47 and permit the same to be withdrawn from engagement with notches 46, the triggers 53 may be swung out of engagement with the head 57 of 35 the locking finger 47, as is shown in Figure 8, by moving the trigger 53 to the dotted position and as the bars 33 and 34 are pulled toward each other, by the actuation of the triggers 32, the fingers 47 may be disengaged from the notches 46 40 of the bars 45 or if desired, the fingers 47 may be released by manually pulling upon the chains 50 at opposite sides of the rack.

As shown in the drawings, the end members 16 support the transversely extending tray supporting rails 23 and 24, and each of these rails supports a tray 60 which is adapted to be firmly anchored in position, and upon which trays 60 may be stacked other trays in nested relation, such as is indicated in dotted lines in Figure 10. 45 The trays are secured to the tray supporting rails 23 and 24 in a similar manner in each instance and it is thought only necessary to describe one set of securing means. Each rail carries a pair of sliding substantially U-shaped 50 yokes 61 which are movable longitudinally upon the rails 23 and 24, as shown, and transversely extending pins 62 are carried by the yoke 61 55 extending across the top face of the rails 23 and 24, as shown in Figure 10. Each yoke 61 carries a 60 pivotally secured tray engaging latch 63 which is provided with an inturned finger 64, the inturned fingers 64 of the latches 63 overhang the edges of the trays 60 for retaining the trays in a set position. A pivotally secured bolt 65 is secured 65 to each latch 63, as shown in detail in Figure 10, the bolt extending down through the slotted portion 27 of the rails 23 and 24. Thumb nuts 66 are carried by the bolts 65 for facilitating the anchoring of the bolts in position and the locking of the tray clamps in a set position upon the supporting rails 23 and 24. The tray clamps constitute the yokes 61, the latches 63, and the bolts 65. In order that the trays 60 may be efficiently supported and braced upon the bottom 70 75

thereof, laterally extending angle braces 67 are secured to the rails 23 and 24, as shown in Figure 2 to engage the bottom of the trays 60.

From the foregoing description and by carefully considering the drawings, it will be seen that a very simple and efficient means is provided for locking the end members 16 which carry the tray supporting rails 23 and 24 in a vertically adjusted position, the parts being held in their proper positions through the medium of the locking fingers 40. These fingers may be drawn out of engagement by the operation of the triggers 32 and the tray rack properly adjusted to the desired height. The pull rods 45 after the end members have been raised to the desired adjusted position, may be pulled vertically and the locking finger 47 may then engage the notch 46. The pull rod 45 upon each side of the frame will then be under proper tension to automatically pull the end members and the tray supporting rails 23 and 24 constituting the tray rack downwardly when these pull rods 45 are released through the swinging of the trigger 53 out of engagement with the head 51, and when the chain 50 is pulled upon each side of the frame. This lowered position is shown in detail in Figure 6. The upper position is shown in Figure 5.

Having described the invention, what is claimed as new is:—

1. A tray rack comprising a pair of end frames, end members vertically adjustable upon said end frames, a tray supporting rail carried by said end members, latching means carried by said end members and engaging said end frames for holding said end members in vertically adjusted relation upon the end frames, and means engaging said end members for exerting an even direct downward pull and for automatically lowering the end members relative to the end frames when said end members are released from the end frames.

2. A tray rack of the class described comprising a pair of end frames, end members vertically adjustable upon said end frames, a tray supporting rail connecting the end members, latching means carried by the end members and engageable with said frames for selectively locking the end members in an adjusted position upon said end frames, and means engaging each end member adjacent each end frame for exerting an even direct downward pull upon said end members and for automatically lowering the end members upon the end frames when said locking means is released, whereby said end members may freely slide downwardly upon said end frames without fear of jamming.

3. A tray rack of the class described comprising a plurality of end frames, each end frame comprising a pair of parallel track rails, end members carried adjacent said rails and provided with shoe blocks slidably mounted upon said rails, locking fingers slidably mounted through said end members, a tray supporting rail connecting the end members, said track rails having spaced notches for receiving said locking fingers for holding the end members in vertically adjusted relation upon said rails, springs for normally holding said locking fingers in a locking position, trigger means for withdrawing the locking fingers to an unlocking position, a pull rod slidably mounted through one of said shoe blocks, one of the shoe blocks carried by each end member, means passing through each end member and releasably engaging said pull rod, means for

exerting a downward pull upon said pull rods whereby the end members will be automatically pulled downwardly when said pull rods are released, and means for normally preventing the release of the pull rods when said locking fingers are released.

4. A device of the class described comprising vertically extending supporting tracks, a tray supporting frame slidably mounted upon said tracks, locking means carried by the tray supporting means for engaging the tracks for holding the tray supporting means in a vertically adjusted position upon said tracks, a pull rod vertically adjustable with respect to said tray supporting means, a locking means carried by the tray supporting means and engaging the pull rod for holding the pull rod and tray supporting means in respective anchored relation, means for normally exerting a downward pull upon said pull rod, means for holding said locking means against releasing action when said tray supporting means is released for sliding movement with respect to said tracks, and means for releasing the tray supporting means from locking engagement with said pull rod.

5. A tray rack of the class described comprising a plurality of vertically extending track rails, a tray supporting means slidably mounted upon said track rails, locking members carried by the tray supporting means and engaging the track rails for locking the tray supporting means in a set position upon the track rails, a pull rod having means for exerting a downward pull thereon carried adjacent the track rails and the tray supporting means, a locking member for locking the tray supporting means in anchored engagement with respect to the pull rod, a trigger for preventing the release of the last mentioned locking member when the first mentioned locking members are released from said track rails for causing said tray supporting means to be automatically pulled to a lowered position, means for releasing said last mentioned locking member, and flexible means normally retained in a slack position connecting the first mentioned locking members and the last mentioned locking member, and trigger means for actuating said locking members.

6. A device of the class described comprising a plurality of end frames, a tray supporting means comprising sectional end members adjustably mounted upon said end frames, each sectional end member comprising a plurality of sections, tray supporting rails carried by the sections, a connecting sleeve for connecting the sections of the end members, one section of each end member having a notch at one end, and transversely extending locking means carried by each sleeve for fitting into said notches.

7. A device of the class described comprising a plurality of end frames, a tray supporting means comprising sectional end members adjustably mounted upon said end frames, each sectional end member comprising a plurality of sections, tray supporting rails carried by the sections, a connecting sleeve for connecting the sections of the end members, one section of each end member having a notch at one end, transversely extending locking means carried by each sleeve for fitting into said notches, and tie rods extending between the tray supporting rails for holding the sections of the end members in anchored relation.

8. A device of the class described comprising a tray supporting means, a tray supporting rail

- carried by said tray supporting means, yokes slidably mounted upon said rail, a pivoted latching member carried by each yoke and having a depending end for firmly gripping the edge of a tray, a locking bolt carried by each latching member, the tray supporting rail being slotted for receiving the locking bolts, and removable means carried by the ends of the bolts for clamping the latch members in a locked position.
- 10 9. A device of the class described comprising vertically extending supporting tracks, a tray supporting frame slidably mounted upon said tracks, locking means carried by the tray supporting means for engaging the tracks and holding said tray supporting means in a vertical-
- 15

ly adjusted position upon said tracks, a pull means vertically adjustable with respect to said tray supporting means, a locking means carried by the tray supporting means and engaging the pull means for holding the pull means and tray supporting means in respective anchored relation, means for normally exerting a downward pull upon said pull means, means for holding said locking means against releasing action when said tray supporting means is released for sliding movement with respect to said tracks, and means for releasing the tray supporting means from locking engagement with said pull means.

ROBERT C. BURNLEY. 15
